ABSTRACT: A tension balancer having a spring-biased indicator with appropriate indicia and means to attach to the thread of a sewing machine. The tension balancer permits the exact adjustment of the proper balance of tension between the needle thread and bobbin thread to provide a perfect stitch. The method of using the tension balancer requires the operator to attach the spring-biased plunger in turn to either the bobbin thread or the needle thread and kinematically adjust the sewing machine to provide the appropriate dynamic tension.

METHOD OF TENSIONING THREAD ON A SEWING MACHINE

BACKGROUND OF THE INVENTION

1. Field of the Invention

This invention relates to an apparatus and method of providing the proper balance of tension between the needle thread and bobbin thread in a sewing machine to provide a correct stitch pattern.

2. Description of the Prior Art

A sewing machine is basically designed to interconnect or lock two separate threads on opposite sides of a piece of fabric or fabrics. This is accomplished by repetitively forcing an upper or needle thread through the fabric and then inserting a lower or bobbin thread through the upper thread to form a closed series of loops. The desired perfect stitch will have its threads locked between the two layers of fabric without any surplus loops on the top or bottom of the material. If the upper thread is too tight relative to the lower thread, the thread will merely lie across the top of the fabric or even break if the tension is beyond its limits of strength. Likewise, if the bobbin or lower thread is too tight, it is also susceptible to breakage and will lie across the bottom of the fabric exposing the loop portion of the upper thread. An improper tension balance can produce irregular stitches, a puckering of the material, skipped stitches, and broken upper and lower threads.

The prior art has sought to incorporate in the sewing machine means for adjusting the tension of both the needle thread and bobbin thread. The normal sewing machine generally has a dial or knob that is inserted between the spool thread and the needle and permits the looping of a portion of the thread through a spring member to vary the thread tension. The lower thread or bobbin thread also utilizes a tension spring on the bobbin that can be adjusted by a screwdriver. The actual adjustment of the sewing machine to provide properly locking stitches is a procedure of trial and error and generally requires a mercerized thread because synthetic threads will normally not break under high tension. The operator will generally set the upper thread tension balance and experimentally make a line of stitching. He then is required to inspect the fabric and the stitch, and if he finds that the seam is puckered, he will know that both tensions are too tight. If he observes that the bottom thread is looped, he will know that the upper thread tension needs to be tightened while, if the top thread lies on the top of the fabric, he will know that he must loosen the upper thread tension. The operator, if the stitching fails on any of the above visual inspections, will be forced to repeat his experiment and continually perform minute adjustments until he has produced a perfect stitch.

The sewing machine operator generally approached the adjustment of his machine by loosening the bobbin thread tension and lowering the dial setting of the needle tension since this will permit him to at least know the direction of adjustment, that is a gradual tightening of the tension during his experimentation. It has also been recommended in the prior art that the stitching itself be grasped and pulled evenly and firmly apart until one or both the threads break. This test is for the purpose of demonstrating the balancing of the tensions between the needle thread and bobbin thread. If both the threads break then the tensions are appropriately balanced. However, if neither thread breaks, the tensions are too loose while if only one of the threads breaks it is indicative of an improper tension balance.

While sewing machines contain the basic elements for effecting an adjusting of the tension balance between the upper or needle thread and the lower or bobbin thread, it is very obvious that the repetitive experimental approach is highly unsatisfactory in time and result. This approach has been found to be highly exasperating to the average housewife and further costly and time-consuming in the commercial environment.

SUMMARY OF THE INVENTION

The present invention provides both the apparatus and method to overcome the problems of the prior art in a simple and efficient manner.

This is accomplished by providing a separate tension balancer that will permit the independent and exact adjustment of both the upper or needle thread and the lower or bobbin thread to provide a perfect stitch. With the use of the apparatus of this disclosure, the upper or needle thread can be quickly and efficiently determined by applying a dynamic tension to the thread and simply dialing the appropriate tension in correlation with the indicia of the tension balancer. Likewise, the lower or bobbin thread can be adjusted by again applying a dynamic tension to the bobbin thread while making appropriate adjustments of the tension screw in correlation with the indicia of the tension balancer.

BRIEF DESCRIPTION OF THE DRAWINGS

FIG. 1 is a segmentary elevational view in cross section showing the device of this invention.

FIG. 2 is a side-elevational view of the tension balancer adjusting the tension on the top thread of the sewing machine.

FIG. 3 is a side-elevational view of the tension balancer adjusting the tension of the bobbin thread.

FIG. 4 is a perspective view of a bobbin case.

FIG. 5 is a cross-sectional view of a perfect stitch.

DESCRIPTION OF THE PREFERRED EMBODIMENT

As illustrated in FIG. 1, the tension balancer 10 comprises a housing 20 which can be a shell of any geometrical configuration. A tubular-shaped penlike configuration has been found to be highly satisfactory. The housing 20 encloses a plunger 14 which has a spring seat 16 at one end and a slot hook 18 to the other end. The hook can assume other shapes as long as it provides an attachment point on the plunger 14. The plunger is appropriately calibrated and marked with indicia points A and B. Point A corresponds to the appropriate tension point of the needle thread while point B corresponds to the appropriate tension point of the bobbin thread. A closure member 22 provides the other seat for the spring music wire 12 and establishes the precompression of the spring assembly. Music wire having a spring constant value of approximately 9.4 oz. per 1 inch has been found to be highly successful. The indicia marks are spaced on the plunger to produce a needle thread tension of approximately 152.5 grams or 5.38 oz. at point A and a bobbin thread tension of approximately 69 grams or 2.44 oz. at point B. This produces a differential of tension of approximately 83.3 grams or 2.94 oz. of tension between the needle thread and the bobbin thread. Actual experiments have shown that it is possible to produce adequate stitches with a plus or minus variation of 10 grams on both the needle and bobbin thread tensions. A cap 24 having a clip 26 has proven to be a convenient modification of the tension balancer. The cap is either snapped or screwed upon the housing 20.

FIG. 5 discloses a perfect stitch configuration where the needle thread 28 is interlocked in the center of the material with the bobbin thread 30. The method of adjusting the sewing machine to produce the ideal stitch, shown in FIG. 5, is the independent adjustment of the upper or needle thread and the lower or bobbin thread by the tension balancer of this invention.

The sequence of adjusting, that is the upper thread or the lower thread, is unimportant since either could be adjusted first. To adjust the needle thread, the sewing machine should be threaded as in normal use with the thread passing from the spool through the upper thread guide and through the upper thread tension control 32 to the thread takeup lever 34. After the thread passes through the thread takeup lever 34, it is attached to the end of the tension balancer plunger 14 through appropriate grip means. The grip means can actually grip onto the thread or, as shown in the simplified embodiment illustrated, can consist of a hook or notch 18 which permits a loop

portion of the thread to be gripped. The pressure foot lever 36 is then lowered into its operative position to place the needle thread 28 in tension. The thread is then gently pulled by the tension balancer 10 with the end of the plunger 14 preferably pointed towards the takeup lever 34. During this pulling motion, the upper thread tension control is adjusted to cause the plunger indicia A to appear at the end of the tension balancer housing. When the indicia A remains steady while the thread is being pulled, the needle thread tension is correct. This dynamic tension is effectively established in one calibration. The thread should slide easily through the adjustment plate of the tension control throughout the entire calibration. If the pressure of the thread against the plunger 14 is not sufficient to force the plunger 14 to extend to the calibration point A, the tension on the thread 28 must then be increased to create sufficient pressure to allow the plunger to extend through the calibration point A. If the tension on the thread is such that the plunger is allowed to extend beyond the calibration point A, tension on the needle thread is too great and therefore the tension must be readjusted by easing the adjustment of the tension control 32 to the point where the thread will slide easily through the adjustment plate while the plunger 14 on the tension balancer 10 remains fixed at the calibration point A.

In adjusting the bobbin tension, the bobbin is inserted into the bobbin case as illustrated in FIG. 4, and installed in the sewing machine in the normal fashion. The bobbin thread 30 is pulled up through the throat plate 38 and an appropriate loop is fastened in the end of the thread and hooked in the notch hook 18 in the plunger 14. The thread is then slowly pulled through the throat plate 38 with the end of the plunger 14 pointing toward the hole in the throat plate 38. When the indicia mark B remains steady at the end of the tension balancer housing, the bobbin thread tension is correct. If the indicia point B is beyond the tension balancer housing, then the tension is too tight while, if it remains within the housing the tension is too loose, and the adjusting screw 42 on the bobbin casing 40 should be appropriately adjusted.

With appropriate modification, this device can be used to set proper tensions on the threads of sewing machines for the most efficient operation of the machine upon unusual materials or unusual stitches such as zigzag stitching or other stitching which requires a measure of tension on the needle thread and bobbin thread to a different degree from normal materials and normal sewing methods. Upon completion of

the special sewing, the operator of the sewing machine can immediately return the machine to its proper and normal adjustment by the use of the tension balancer 10 of this invention.

What is claimed is:

5. 1. A method of tensioning a thread on a sewing machine by the use of a calibrated tension balancer having a resiliently bias plunger with indicia comprising the steps of:
  - attaching the plunger of the tension balancer to the thread at a point after it has passed through an adjustable tension regulator on the sewing machine,
  - moving the tension balancer away from the tension regulator, and
  - simultaneously adjusting the tension regulator in correlation with the indicia on the plunger until the appropriate tension is produced on the thread.
10. 2. The method of claim 1, where the appropriate tension force is adjusted to be not less than 59 grams nor more than 162.5 grams.
15. 3. A method of adjusting a sewing machine to produce an optimum stitch by the use of a calibrated tension balancer having a resiliently bias plunger with indicia comprising the steps of:
  - a. attaching the plunger of the tension balancer to the needle thread at a point on the thread after it has passed effectively beyond the adjustable needle thread tension regulator on the sewing machine,
  - b. moving the tension balancer away from the needle thread tension regulator,
  - c. adjusting the needle thread tension regulator in correlation with the indicia on the plunger until the appropriate tension is produced on the needle thread,
  - d. removing the needle thread from the plunger and attaching the plunger to the bobbin thread after it has passed effectively beyond the bobbin tension regulator on the sewing machine,
  - e. moving the tension balancer away from the bobbin, and
  - f. adjusting the bobbin tension regulator in correlation with the indicia on the plunger until the appropriate tension is produced on the bobbin thread.
20. 4. The method of claim 3, where the needle thread tension force is adjusted to be approximately 83 grams greater than the bobbin thread tension force.
25. 5. The method of claim 4, where the needle thread tension force is approximately 152.5 grams.
